DESIGN FOR A SEWING MACHINE FRAME

Norman Wonnacott, Scarsdale, N. Y., assignor to
Willcox & Gibbs Sewing Machine Company,
New York, N. Y., a corporation of New York

Application February 13, 1941, Serial No. 98,979

Term of patent 14 years

To all whom it may concern:

Be it known that I, Norman Wonnacott, a citizen of the United States, residing at Scarsdale, in the county of Westchester and State of New York, have invented a new, original, and ornamental Design for a Sewing Machine Frame, of which the following is a specification, reference being had to the accompanying drawing, forming a part thereof, and in which—

Figure 1 is a side elevational view of a sewing machine frame showing my new design;

Fig. 2 is a front elevational view thereof; and
Fig. 3 is a top plan view of the design shown
in Figs. 1 and 2.

The characteristic features of my design reside in the portions shown in full lines.

I claim:

The ornamental design for a sewing machine frame, substantially as shown and described.

NORMAN WONNACOTT.
